(57) **CLAIM**

The ornamental design for a tube label, as shown and described.

DESCRIPTION

FIG. 1 is a front view of a tube label showing my new design, in use with the backing removed and attached to a tube.

FIG. 2 is a front view thereof;

FIG. 3 is a back view thereof;

FIG. 4 is a side view (opposite side view is mirror image) thereof; and,

FIG. 5 is a top view (opposite side view is mirror image) thereof.

The broken lines in FIGS. 1 and 2 showing the tube, text and barcode illustrate environment and form no part of the claimed design.

1 Claim, 3 Drawing Sheets

FIG. 1

FIG. 2

FIG. 3

FIG. 4

FIG. 5
